UNITED STATES PATENT OFFICE.

HERBERT F. OBERGFELL, OF RIVER FOREST, ILLINOIS, ASSIGNOR TO AUTOMATIC ELECTRIC INC., OF CHICAGO, ILLINOIS, A CORPORATION OF DELAWARE.

DESIGN FOR A TELEPHONE SET.

Application filed October 22, 1927. Serial No. 23,846. Term of patent 14 years.

To all whom it may concern:

Be it known that I, HERBERT F. OBERGFELL, a citizen of the United States of America, residing at River Forest, in the county of Cook and State of Illinois, have invented a new, original, and ornamental Design for a Telephone Set, of which the following is a specification, reference being had to the accompanying drawings, forming a part thereof.

I claim:

The ornamental design for a telephone set, as shown.

In testimony whereof, I have hereunto set my hand this 17th day of October, 1927.

HERBERT F. OBERGFELL.
